UNITED STATES PATENT OFFICE.

CARL LAGER, OF BALDWINSVILLE, NEW YORK

HIGH-LIFT CENTRIFUGAL PUMP.

No. 897,469.

Specification of Letters Patent.

Patented Sept. 1, 1908.

Application filed June 7, 1904. Serial No. 211,450.

To all whom it may concern:

Be it known that I, CARL LAGER, of Baldwinsville, in the county of Onondaga, in the State of New York, have invented new and useful Improvements in High-Lift Centrifugal Pumps, of which the following, taken in connection with the accompanying drawings, is a full, clear, and exact description.

This invention relates to improvements in high-lift centrifugal pumps, in which a plurality of pumping runners are connected in series and operate to force the water successively from one to the other, each adding pressure to that preceding it.

In any centrifugal pump receiving water in one side or end there is always an end pressure toward the suction opening corresponding to the area of such opening multiplied by the pressure per unit of such area, and therefore if the suction openings of the several runners were all on the same side the end thrust or pressure in the direction of such openings would be substantially equal to the sum total of the pressures on all the runners.

My object, therefore, is to establish an equilibrium of this pressure in all directions and to balance the runners and its driving shaft by a particular relative arrangement of the runners and intercommunicating passages so that the end pressure on one or more runners in one direction is counteracted by a corresponding pressure on one or more of the other runners in the opposite direction, thereby preventing excessive end thrust in either direction.

Another object is to construct the case and diaphragms in separate parts so that each may be easily and quickly machined and fitted and assembled without employing special machinery or tools.

Other objects and uses will appear in the following description.

In the drawings—Figure 1 is a top plan of a centrifugal pump embodying the various features of my invention. Figs. 2, 3, 4, and 5 are sectional views taken respectively on lines 2—2, Fig. 1 and 3—3, 4—4, and 5—5, Fig. 2. Figs. 6 and 7 are perspective views of half sections of one of the end diaphragms and the intermediate diaphragm.

The pump-case is preferably made in two parts of cast metal consisting of a lower half-section —1— and an upper half section —2— both of which parts are formed with a semi-cylindrical opening extending from end to end and are secured together at their meet-

ing faces by suitable means, as bolts, —3—, thereby forming a rigid case or shell with a central lengthwise opening —4—, the ends of which are closed by suitable caps or circular plates —5— and 5'— having central openings —6—. These plates are secured to the adjacent ends of the shell sections by suitable means, as bolts —7—, and are provided with central end journal bearings 60 —8— and 8'— in which is rotatably mounted a driving shaft —9—, the bearing —8'— being closed at its outer end while the other bearing —8 is provided with a suitable stuffing box through which the shaft projects to 65 be connected to any power transmitting mechanism, not shown.

Secured to the shaft —9— between the heads or caps —5— and 5'— are a series of pumping runners —10—, —11—, 12— and 75 13— which are spaced apart by spacing sleeves —14— and are each formed in one side or face with a central water inlet or passage —15— extending inwardly and radially through the periphery of the runner, the radial passage being divided at intervals by vanes or partitions —16— which are convexed in the direction of rotation to facilitate the expulsion of the water.

The interior of the shell is divided at intervals by transverse partitions or diaphragms —17—, 17'— and 18— to form a series of compartments in which the runners revolve and each diaphragm is provided with a central shaft bearing —19— and with one or 80 more annular ribs —20— which are fitted in corresponding grooves —21— in the inner wall of the shell so that the shell sections when clamped together operate to clamp the diaphragms rigidly in place.

In order to obviate excessive end thrust of the runners and their driving shaft the inlets of certain runners representing a definite pressure are arranged to face in one direction while the inlets of the remaining runners representing a corresponding pressure are caused to face in the opposite direction and I have therefore shown the runners 10— and 13— as having their inlets facing in one direction, as to the right, and the inlets of the runners 105 —11— and 12— as facing in the opposite direction or to the left, as best seen in Fig. 2, this arrangement causing the inlets of the runners 10 and 11— to face each other which is also true of the inlets 12— and 13—. This necessitates a special construction and arrangement of the diaphragms and their water

passages, and also of the water passages of the shell or casing and, to this end, the diaphragm —17— is interposed between the runners —10— and —11— and is formed with diametrically opposite water ways —23— and —24— which are separated by an oblique partition —25—, the passage —23— leading from an inlet —26— in the lower shell section —1— to the central passage of the runner —10— at one side of the partition —25—, and the passage —24— communicates with the inlet of the runner —11—.

The shell or inclosing case is formed with a series of spiral conduits or passages —27—, 15 28—, 29— and —30, which encircle their respective runners 10—, —11—, 12— and 13— and communicate with the compartments in which they revolve. The passage —27— receives the water discharged from the periphery of the runner 10— and terminates in an outside by-pass —27'— which discharges into the water-way —24—, the water being then deflected by the oblique partition —25— into the central inlet of the runner —11—, 25 from which it is discharged into the spiral passage —28—, and thence through an outside by-pass 28'— and into the water-way —32— of the diaphragm —18—. This diaphragm —18— is of the same construction as the diaphragm —17— and located between the runners —12— and 13— and is formed with diametrically opposite water-ways —32 and 33— and an oblique partition —34— which separates said water-ways and also the central inlets in the runners —12— and 13— so that the water entering the passage —32— is deflected by the partition —34— into the central inlet of the runner 12— from which it is discharged into the spiral passage —29—. This passage —29— has a lateral extension —35— which discharges into the passage —34— at the lower front side of the partition —34— whereby the water is deflected into the central inlet of the runner —13— and 45 from this runner is discharged into the spiral water-way —30—, and finally out through a discharge nozzle —36— also in the lower shell section —1—.

It is now apparent that the water is drawn 50 through the inlet —62— centrally into the right side of the runner —10— from which it discharges through the passages —27—, 27'— and —24— and enters centrally into the left side of the runner 11, thence into the 55 passages —28—, 28' and 32—, centrally into the left side of the runner 12— and back through the passages 29—, 35— and 33— into the right side of the runner 13— from which it is finally discharged through the 60 passage —30— and outlet nozzle —36—.

Now, if the pressure on the pump runner —10— is ten pounds, the pressure on the run-

ner 11— will be twenty pounds; that on the runner —12— thirty pounds, and that on the runner —13—, forty pounds—these 65 pressures being all in the direction of their respective inlets. But the inlets of the runners —10— and —13— face in the same direction and, therefore, the pressure in this direction is ten pounds on the runner —10—, and forty pounds on the runner —13—, or a total of fifty pounds, while the inlets of the runners —11— and —12— face in the other direction, and therefore, the pressure in this direction is twenty pounds on the 75 runner —11— and thirty pounds on the runner —12—, or a total of fifty pounds— which establishes an equality of pressure upon the pump runners and maintains them and the shaft in equilibrium to prevent end 80 thrust in either direction.

It will be observed upon reference to Figs. 2 and 6 that the deflecting plates or partitions of the diaphragms —17— and —18— extend from one side of the circular inlet of 85 one of the runners to the opposite side of the inlet of the adjacent runner, thereby separating the inlets of adjacent runners from each other.

The diaphragm 17'— differs from the 90 other diaphragms in that it is merely a dividing partition without any passages and serves to separate the runners —11— and 12— and passages —28— and —30—.

In assembling the parts of this pump the 95 runners, diaphragms and separating sleeves are placed over the end of the shaft in the order shown in Fig. 2 and the runners and separating sleeves are then clamped against a shoulder —38— at one end of the shaft by 100 means of clamping nuts —39— which are engaged with the opposite end of said shaft, the runners being further locked to the shaft by suitable keys.

Having thus described my invention what 105 I claim and desire to secure by Letters Patent is—

In a multistage centrifugal pump, a casing having impeller chambers and annular delivery passages, and an inlet between the delivery passages, impellers in said chambers having their inlets facing each other, a diaphragm separating said chambers and having separate passages, one connecting the casing inlet to one of the impeller inlets, and the 115 other connecting the delivery of the last mentioned impeller with the inlet of the other impeller.

In witness whereof I have hereunto set my hand this 1st day of June 1904.

CARL LAGER.
